UNITED STATES PATENT OFFICE.

GEORGE HENRY GIDDINGS, OF ILION, NEW YORK.

SPLIT SAFETY-POST AND INDICATOR FOR DOUBLE-BARREL GUNS.

1,222,755.

Specification of Letters Patent.

Patented Apr. 17, 1917.

Application filed August 12, 1915. Serial No. 45,120.

To all whom it may concern:

Be it known that I, GEORGE H. GIDDINGS, a citizen of the United States, residing at Ilion, in the county of Herkimer and State of New York, have invented certain new and useful Improvements in Split Safety-Posts and Indicators for Double-Barrel Guns, of which the following is a specification.

This invention relates to an improvement upon the breech loading fire arm described and shown in my application filed March 2, 1914, Serial Number 821,947 and which was allowed March 25, 1915.

The invention relates especially to that portion of the mechanism connected with the safety post and indicator, and co-operating with the hammer and the sear.

The device relates to double-barrel guns and the objects of the invention are to allow one hammer to be cocked and made safe while the other side or hammer is uncocked and off safe. This is desirable in case one side of the mechanism is out of order, permitting the operation of the other side and use of the other barrel, and still permit operation of the safety device. This also enables the person using the gun and who wishes to use but one barrel to make the other barrel safe thereby making certain that the use of one barrel will not jar off the other as is sometimes the case when the notches become worn. This feature of my device I term an emergency safe. These objects are secured by forming the safety post and buttons in two parts, thereby forming a split safety post, while the position of the buttons act as a safety indicator.

The invention also consists of the novel features of construction hereinafter described, pointed out in the claims and shown in the accompanying drawings in which:

Figure 1 is a longitudinal sectional view showing the right hand lock plate with hammer and sear attached, and with right hand safety post and button in forward or off safe position.

Fig. 2 is a similar view with the hammer half way back to cocked position, the post and button being also in half position.

Fig. 3 is a similar view, the right hand hammer being all the way back and the right hand post and button being in safe position, with the left hand post and button

remaining in forward or off safe position, as in Figs. 1 and 2.

Fig. 4 is an inverted plan view of the tang showing the springs and split safety post both in forward position.

Fig. 5 is a detail section on the line 5—5 of Fig. 1.

Fig. 6 is a side elevation of the springs, safety post and button, one button and post being in forward position and the other 65 being in rear or safe position.

Fig. 7 is a detail side view of one of the buttons.

Fig. 8 is an end view of the two buttons fitted together.

In these drawings 1 indicates the gun frame and 2 the tang which is provided with a suitable slot 3 over which the button works and upon its under side and to the rear of the slot the tang is provided with 75 notches 4. A lock plate 5, hammer 6 and sear 7 are also provided. Instead of a solid post the post is split longitudinally thereby forming right and left hand posts 8 adapted to work side by side. Each post has its 89 spring 9 and each spring is provided with a roller 10, these rollers co-operating with the notches 4 as indicated in the drawings. The button 11 is also split longitudinally, each half of the button having a shank 12 85 which works in the slot 3 and each spring 9 is suitably slotted to receive a reduced portion 12^a of one of the shanks 12, as shown most clearly in Figs. 4, 5 and 6.

From Fig. 2 it will be noted that the right hand hammer is half way back, that the right hand safety post, its spring, its roller and the right hand half of the safety button are also half way back to safe position, and that in this position the right hand safety 95 post is engaged by the upturned rear end portion of the sear, and that the rear end of the sear prevents further rearward movement of the button and post.

This is due to the fact that when the hammer is in this position a cam 6^a which is formed upon the hammer adjacent the hammer notch 6^b bears upon the forward end of the sear and holds it elevated at the rear end until the hammer is entirely back when the cam 6^a will clear the forward end of the sear thereby permitting the rear end to drop so that the post will clear it, or will pass into position immediately above it, preventing the rear end of the sear from rising 110

while the button is in safe position, the forward end of the sear engaging the hammer notch 6^b. This cam projection 6^a is an essential and important part of the present improvement as it is this feature which prevents the post being moved back when the hammer is half cocked.

With the solid safety post with one hammer down it is impossible to put the safe on 10 the side with the hammer cocked, due to the sear on the uncocked side being higher at the rear end than the one that is cocked, but with the safety posts acting independent of each other, one hammer can be cocked 15 and made safe, while the other side is uncocked and off safe.

It will also be noted that in addition to having a safety device I have also an indicator of the position occupied by each hammer, as pressure of the thumb on the button 20 will show the position of either hammer, for if the button will not go back to safe position it shows conclusively that the hammers are not cocked. If one half of the button 25 will move back it will show exactly the position of one hammer with respect to the other. The advantages and operation of the invention will be apparent to those skilled in the art to which it relates.

30 What I claim is:

1. In a safety device of the kind de-

scribed, a sectional safety button, a sectional safety post, each section of the button cooperating with one of the post sections, pivoted sears having rearward end portions 35 acting as stops to rearward movement of the post sections, and hammers having cam portions adapted to engage said sears and to hold the rear end portions of the sears in post stopping position, said cams becoming 40 disengaged when said hammers reach their rearmost position, the said hammers, sears and post and button sections having independent movement, as and for the purpose set forth.

2. In a device of the kind described a safety button split longitudinally to form two sections, each section having a shank, and each shank having a reduced portion, a combined safety post and spring also 50 split longitudinally to form two sections, the button shanks having their reduced portion passing respectively through the springs of the safety post sections, and hammers and sears, the sears cooperating with 55 said post sections.

In testimony whereof I affix my signature in the presence of two witnesses.

GEORGE HENRY GIDDINGS.
